Primary Examiner — Lauren R Calve(74) *Attorney, Agent, or Firm* — Workman Nydegger(57) **CLAIM**

The ornamental design for a recreational vehicle door handle, as shown and described.

DESCRIPTION

FIG. 1 is a front perspective view of a recreational vehicle door handle;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof; and,

FIG. 8 is a left elevational view thereof.

The broken lines (dash dash) included in the Figures illustrate environment or portions of the recreational vehicle door handle that form no part of the claimed design. The boundary lines (dash dot) included in the Figures represent unclaimed boundaries that form no part of the claimed design.

1 Claim, 6 Drawing Sheets(56)
